ENVELOPE

Milton Kahn, Long Island City, N. Y., assignor to
 Novelart Mfg. Co., New York, N. Y., a firm

Application August 11, 1938, Serial No. 224,311

3 Claims. (Cl. 229—82)

This invention relates to envelopes of the type wherein sealing of the envelope is performed without requiring moistening of the adhesive substance, and its principal object is to provide a simplified, conveniently and economically manufactured, economically salable, conveniently utilizable, strong, durable, and improved envelope of this type.

Another object is to provide an envelope of the above type having improved means for the concealment of its adhesive coats prior to the normal utilization of the envelope.

A further object is to provide an envelope of the above type having improved means to prevent contact of its adhesive coats, when its sealing flap is folded in the packing of the envelopes.

A still further object is to provide an envelope, which, while embodying the aforesaid advantages, will possess an outward appearance resembling that of the normal letter envelope.

Other objects and advantages will hereinafter appear.

In the accompanying drawing,

Fig. 1 is a plan view showing the blank or integral sheet from which the letter envelope of the invention is made.

Fig. 2 is a rear view elevation of the envelope of this invention, as it appears when in normal state, or prior to utilization and sealing.

Fig. 3 is a transverse-sectional end elevation of the envelope shown in Fig. 2.

Fig. 4 is a view similar to Fig. 2, but showing the envelope as it appears when in completely sealed state.

Fig. 5 is a transverse-sectional end elevation of the envelope, taken on the line 5—5 of Fig. 4.

As illustrated in Fig. 1, the letter envelope is made of a single integral blank sheet 1, comprising a usual addressing front wall 2, a rear wall 3, side flaps 4, a sealing flap 5, and from the terminal edge 6 of rear wall 3 projects a tab 7 as shown. The rear wall 3 is provided with a slot 8 which is parallel to its edge 6. Upon the area of tab 7 and the rear wall 3 between said tab and the slot 8 is provided a coating 9 of dry adhesive substance of a type which, whether moistened or unmoistened, will not stick or adhere to uncoated areas of paper, but will firmly stick to the same adhesive substance forming a coating of another portion of paper. Any suitable substance forming the coating 9 may be resorted to, such as a solution of para rubber in gasoline, or any other known material which will carry out a similar function. The

5 closing flap 5 is provided with a corresponding area carrying similar dry adhesive coating 10, while the ends of side flaps 4 have usual glued areas 11.

In the making of the envelope, the tab 7 is folded against the undersurface of the rear wall 3, along score line 12 that concides with the terminal edge 6, while its coating 9 is adhered to the coated area 13 of said wall, and thereafter the envelope is folded up and completed in the usual manner along score lines 14, the side flaps 4 being folded against the inner surface of front wall 2 and the rear wall 3 being adhered to the glued portions 11 of said flaps, in the manner illustrated in Fig. 2. As thus completed, the top or terminal edge 6 of the rear wall 3 is in a greatly strengthened condition, due to the folding thereabout of the tab 7 against the undersurface of said wall, while the area of the latter between said edge and its slot 8 is particularly reinforced owing to the adherence to its undersurface of the tab 7, which is thus in turn freely suspended below the slot 8 and lies between the walls 2, 3. As in a usual letter envelope, the coating 10 of flap 5 normally appears concealed, as is also the entire tab 7 with its coating 9.

When it is desired to utilize and seal the envelope, the leading portion of the sealing flap 5 is passed through the slot 8 to a position underneath the rear wall 3, and between said wall and the tab 7, so that its coating 10 is in registry with the coating 9 of the latter, as clearly illustrated in Figs. 4, 5, the former figure being presented as having paper portions torn away for clarifying purposes. Upon then applying pressure against the rear wall 3 and upon the flap 5 the latter adheres firmly to the tab 7, through the action of the dry adhering coatings 9, 10, whereby an efficient sealing of the envelope is effected. It will be noted that by virtue of the foregoing provisions of this envelope, not only will there be no danger of its sticking to any other paper or other envelope material in the packing of the envelopes, but its adhesive coatings 9, 10 will be both normally concealed, to obviate exposure, disintegration of the coatings, catching of dust, dirt, or other matter, or producing other injury to the dry adhering coatings. While the letter envelope of this invention is provided with efficient sealing means therefor, its appearance nevertheless resembles that of a regular or conventional letter envelope, which advantage is of utmost importance to this type of article.

Having thus described my invention, I claim:

1. A dry adhering envelope having the combination of a front wall, a rear wall, a closing flap forming part of said front wall folding over said rear wall, said rear wall having a slot, said rear wall having a tab integral therewith and projecting therefrom beyond its topmost confine, said tab being folded to lie against the undersurface of said rear wall and having a dry adhering coat facing said undersurface, the undersurface of said flap having a dry adhering coat, and said flap being adapted to pass its leading portion through said slot to bring its coat into registry with the coat of said tab.

2. A dry adhering envelope having the combination of a front wall, a rear wall, a closing flap forming part of said front wall folding over said rear wall, said rear wall having a slot, said rear wall having a tab integral therewith and projecting therefrom beyond its topmost confine, said tab being folded to lie against the undersurface of said rear wall and having a dry adhering coat facing said undersurface, said rear

wall and said tab having portions of their surfaces in adherence with each other, the undersurface of said flap having a dry adhering coat, and said flap being adapted to pass its leading portion through said slot to bring its coat into registry with the coat of said tab.

3. A dry adhering envelope having the combination of a front wall, a rear wall, a closing flap forming part of said front wall folding over said rear wall, said rear wall having a slot, said rear wall having a tab integral therewith and projecting therefrom beyond its topmost confine, said tab being folded to lie against the undersurface of said rear wall and having a dry adhering coat facing said undersurface, said rear wall and said tab having portions of their surfaces in adherence with each other by dry adhering coatings, the undersurface of said flap having a dry adhering coat, and said flap being adapted to pass its leading portion through said slot to bring its coat into registry with the coat of said tab.

MILTON KAHN.
